UNITED STATES PATENT OFFICE.

WILHELM SCHMIDT AND PETER THOMSEN, OF CASSEL-WILHELMSHÖHE, GERMANY,
ASSIGNORS TO SCHMIDT'SCHE HEISSDAMPF-GESELLSCHAFT M. B. H., OF CASSEL-
WILHELMSHÖHE, GERMANY, A CORPORATION OF GERMANY.

SUPERHEATER FOR LOCOMOTIVE-BOILERS.

1,114,812.

Specification of Letters Patent. Patented Oct. 27, 1914.

Application filed April 28, 1910. Serial No. 553,112.

To all whom it may concern:

Be it known that we, WILHELM SCHMIDT and PETER THOMSEN, both subjects of the King of Prussia, Emperor of Germany, and residents of Cassel-Wilhelmshöhe, Germany, have invented certain new and useful Improvements in Superheaters for Locomotive-Boilers, of which the following is a specification.

10 Our invention relates to locomotive superheaters of the general character disclosed in various patents previously issued to us, or one of us, commonly spoken of as smoke tube superheaters, in which superheater tubes are arranged in the smoke tubes (fire tubes) through which the furnace gases are carried. Generally these superheater tubes have been placed in special smoke tubes of greater diameter than the remaining smoke 15 tubes thereby requiring the boiler to be specially built for the purpose at a substantially increased cost. Not only this but, whereas to secure maximum efficiency a boiler should have the largest possible number of smoke tubes of the thinnest possible material, these larger diametered smoke tubes are necessarily fewer in number and of considerably heavier gage. Expansion and contraction, also, make it much more difficult to maintain tight joints between the smoke tubes and the tube sheets into which they are expanded where the former are of large diameter than when the diameter is small. And, when tubes of different diameters are expanded into the same tube sheet the unequal expansion of the different sized tubes constitutes an obstacle to the maintenance of tight joints.

20 The object of our present invention is to provide an arrangement of the superheater tubes or loops such that they may be placed in the normal and regular smoke tube of the usual locomotive so that no special preliminary construction is required and as many or as few smoke tubes may be occupied as desired. Such a construction is of advantage not only in connection with new locomotives, but in connection with old non-superheater locomotives which can thus readily have a superheater incorporated with them without reconstructing the entire boiler as is usually necessary in applying superheaters of this class to the older locomotives.

25 A further object of our invention is to

group the superheater loops and to so arrange such ends as go to the steam headers as to enable individual superheater elements (or units) to be conveniently inserted and removed; also, so that a convenient and interchangeable fastening means may be employed for attaching said ends to the steam collectors; also, so that the course of the steam through individual elements or units may be readily and quickly traced and joints quickly located in case of leakage or for other purposes.

30 A still further object of our invention is to provide a grouping of superheater loops and an arrangement of their ends so that the ends of the smoke tubes, as they join the tube sheet of the smoke box, are fairly free from obstruction and open to inspection.

35 Other objects will appear as the specification proceeds.

40 In the construction herein described, since any number of smoke tubes may be used to inclose superheater loops up to the total number of smoke tubes embodied in the boiler, the individual superheater loops may be made shorter than usual, so that the return bends thereof may be placed in a cooler part of the smoke tube; in this way said bends are less liable to burn out. This also renders unnecessary the use of a damper or equivalent means to cut off the flow of hot 45 gases when the boiler is first started up or when engine is running with steam shut off.

50 Still another advantage gained by our present improved construction is a simple arrangement of steam headers, which is compact and out of the way and in which cooling of the superheated steam header by reason of proximity of the saturated steam header may be minimized.

55 Referring to the drawings, Figure 1 represents a transverse section through one half of the smoke box of a locomotive equipped with a preferred form of our improvement herein described; Fig. 2 represents a horizontal section along the line 2-2 of Fig. 1; Fig. 3 is a detail, part section, showing several groups of superheater loops arranged according to a modified form of our invention; Fig. 4 represents a section along the line 4-4 of Fig. 3; Fig. 5 is a view similar to Fig. 3, representing still another modification of our invention and Fig. 6 is a section along the line 6-6 of Fig. 5; Fig. 7 is

a view similar to Fig. 1 showing another modification of our invention; Fig. 8 is a section taken along the line 8-8 of Fig. 7 and Fig. 9 represents a section taken along the line 9-9 of Fig. 7.

In Figs. 1 and 2, *a* is the smoke box barrel, *b* the front tube plate, *c* the smoke tubes and *d* and *e* steam collectors arranged side by side and of rectangular section. Collector *d* is the saturated steam header and receives steam from the boiler by means of pipe *f*, while *e* is the superheated steam collector. The superheater consists of 12 rows of superheating loops *g*, which are arranged in 12 rows of smoke tubes, three tubes in each row being used for the purpose. Each superheating loop *g* is U-shaped and the two ends thereof are connected respectively to the saturated and superheated steam collectors *d* and *e* so that all the loops are parallel. The arrows, Fig. 2, show the course of the steam through said superheater loops. In bringing out the ends of the superheater loops of the two top rows, it will be noticed that these ends lie in and connect to the two steam collectors in one and the same plane and that this plane is the meridian plane of the top row. In the same way the ends belonging to the elements of the third and fourth rows lie in a single plane and this plane is the meridian plane of the fourth row. In this way a very generous vertical distance is obtained between the ends of the superheater loops as they join the steam headers so that we have sufficient room to utilize a connecting clamp *h* provided with an intermediate screw bolt and nut *h'* the ends of said bolts being forked to rest upon the terminal disks *i* into one of which each superheater element end is expanded. The same scheme is used for the remaining rows of superheater elements. By thus arranging the rows of connecting points of superheater elements and steam headers at these considerable distances apart and thereby using the long clamp pieces *h*, we are able to make these pieces strong and substantial; they are also very accessible and easily removed individually. The attaching bolts and their nuts *h'* are also easily gotten at.

It will be noted that the superheater loop ends which are in one plane (the ends coming from two adjacent rows of smoke tubes) are vertically in line with the corresponding ends coming from every other set of two smoke tube rows. Thus all the ends from the different pairs of rows which go to the superheated steam collector are arranged vertically as to one another, and similarly as to the ends which go to the saturated steam collector. This permits the use of steam collectors of a simple rectangular section and thereby reduces the cost of manufacture; heat losses in the collectors

are also reduced since there is a minimum number of separate walls between saturated and superheated steam collectors.

In the modification shown by Figs. 3 and 4 each individual superheater element or unit consists of two U-shaped loops arranged in series in adjacent smoke tubes belonging to two neighboring smoke tube rows. Here the steam collectors are not cast in one piece (as in Figs. 1 and 2), but comprise separate castings between which may be left an air space; or if preferred, a heat insulating medium may be inserted so as to diminish any flow of heat from the superheated steam collector to the saturated steam collector and consequent cooling of the superheated steam.

Figs. 5 and 6 show still another arrangement in which the smoke tubes are placed one above the other, instead of staggered as in the previous figures. Here the plane in which the superheater unit ends are carried out is midway between the rows of smoke tubes. Each superheater unit consists of two U-tubes, in vertically adjacent smoke tubes, arranged in series. In this modification the rows of superheater element ends are equidistant, although since the smoke tubes are necessarily farther apart than when staggered, the actual distance between the planes of these ends may be the same so that connecting clamps *h* may be used of the same length as in the arrangement shown in Figs. 1-4.

Figs. 7 to 9 show still another modification of our invention. Here each superheating unit consists of two U-tubes arranged in series in two smoke tubes in the same vertical line but in rows separated by an intervening row. The two ends are carried vertically away from one another instead of toward one another as in Fig. 5, *e.g.* This makes it possible to bring out the saturated steam ends of the superheating elements belonging to the four top rows of smoke tubes in one plane and all of the corresponding superheated steam ends in another plane. The same may be done for the next four rows of smoke tubes and again for the last four rows of smoke tubes. The steam collectors are then arranged as one casting containing four chambers in which the saturated steam and superheated steam is alternated. Thus in Fig. 7, *n* is a saturated steam collector and *m* a superheated steam collector. In this way each of the inner pairs of central planes containing superheater element ends employ common steam chambers.

The modification shown in Figs. 7 to 9 has a further advantage over the previously described forms in that the saturated steam end and the superheated steam end of each complete superheating unit lie vertically one above the other. Each connecting clamp *h*,

- therefore, serves to completely clamp and hold in position one complete superheater unit, which may, consequently, be removed or replaced at once by simply unscrewing 5 the one nut h' of that particular clamp.
- It should be understood that we have described herein only one-half of the boiler. The other half would be identically the same as the half shown so that the boiler as a 10 whole would have an identical system of steam collectors on each side with groups of superheater pipes separated along the vertical center line of the boiler and joined to said collectors.
15. We claim:
1. In combination with a locomotive boiler provided with smoke tubes, a superheater comprising a plurality of units constituted of loops arranged in said tubes all 20 the ends of said units belonging to a plurality of smoke tube rows being bent into a common plane and, in said plane, the saturated steam ends and the superheated steam ends being arranged in two separate 25 groups.
  2. In combination with a locomotive boiler provided with smoke tubes, a superheater comprising a plurality of units each constituted of a plurality of loops arranged 30 in said tubes all the ends of said units belonging to a plurality of smoke tube rows being bent into a common plane, and, in said plane, the saturated steam ends and the superheated steam ends being arranged in 35 two separate groups.
  3. In combination with a locomotive boiler provided with smoke tubes, a superheater comprising units each constituted of single U shaped loops arranged, one loop to 40 a tube, in said tubes all the ends of said units belonging to a plurality of smoke tube rows being bent into a common plane and, in said plane, the saturated steam ends and the superheated steam ends being arranged 45 in two separate groups.
  4. In combination with a locomotive boiler provided with a plurality of grouped rows of smoke tubes, a superheater comprising units constituted of loops arranged in 50 said tubes, the ends of said units belonging to each different group of smoke tube rows being bent into a common plane in which plane the saturated steam ends and the superheated steam ends are arranged in two
- separate groups said planes being, further, alternately remote from and closely adjacent to one another.
5. In combination with a locomotive boiler provided with a plurality of smoke tubes, a superheater comprising units constituted of loops arranged in said tubes, all the ends of said units belonging to a plurality of smoke tube rows being bent into a pair of common planes substantially parallel to the planes of said smoke tube rows 65 of which one plane contains all the saturated steam ends and the other plane all the superheated steam ends.
6. In combination with a locomotive boiler provided with a plurality of smoke tubes, a superheater comprising units constituted of loops arranged in said tubes one loop to a tube all the ends of said units belonging to a plurality of smoke tube rows 70 being bent into a pair of common planes substantially parallel to the planes of said smoke tube rows of which one plane contains all the saturated steam ends and the other plane all the superheated steam ends.
7. In combination with a locomotive boiler provided with a plurality of smoke tubes, a superheater comprising units constituted of loops arranged in said tubes, the ends of said units being bent into a number 75 of common planes in such a manner that pairs of planes of saturated steam ends alternate with pairs of planes of superheated steam ends.
8. In combination with a locomotive boiler provided with a plurality of smoke tubes, a superheater comprising units constituted of loops arranged in said tubes, the ends of said units being bent into a number 80 of common planes in such a manner that pairs of planes of saturated steam ends alternate with pairs of planes of superheated steam ends the distance between said pairs being, further, substantially greater than 85 the distance between the members of a pair.
- In testimony whereof we have hereunto 90 set our hands in the presence of two subscribing witnesses.
